UNITED STATES PATENT OFFICE

2,622,068

PROCESS OF MAKING HEAT DRIED DETERGENT COMPOSITIONS CONTAINING FORM II SODIUM TRIPHOSPHATE

Elbert S. Hizer, Cincinnati, Ohio, assignor to The Procter and Gamble Company, Ivorydale, Ohio, a corporation of Ohio

Application June 4, 1948, Serial No. 31,174

3 Claims. (Cl. 252—138)

1

The present invention relates to a method for the manufacture of detergent mixtures containing alkali metal triphosphates (sometimes called alkali metal tripolyphosphates), and particularly to the incorporation of slowly hydrating anhydrous triphosphates in aqueous detergent compositions.

Some varieties of triphosphate in finely divided form exhibit the undesirable property of forming lumps that dissolve very slowly in water even though the mixture is well stirred. The tendency to form lumps or agglomerates, I have found, varies with the phase or form of crystalline structure of the phosphate. Thus I find that finely divided triphosphates containing substantial amounts of the high temperature form, usually referred to as Form I, show a very marked tendency to lump when stirred into aqueous fluids even though the mixture is stirred vigorously. However, I have found that comparably finely divided triphosphates of the low temperature phase usually referred to as Form II, show little or no tendency to agglomerate under like conditions, and the present invention relates to the use of these Form II triphosphates in the manufacture of detergents.

Prior to the present invention, however, triphosphates of the Form II variety have had the objectionable tendency, when used in the manufacture of heat dried detergent compositions, of producing powders of a sticky nature that are not free flowing and that cake badly under slight pressure in storage bins, packing machines and in packed cartons.

In order to avoid a damp product which would lump and ball much worse, extreme atomization has been used to facilitate the spray drying of such compositions causing them to be fragile and dusty as well as sticky.

By "sticky" I refer to an objectionable tendency of the individual spray dried granules to agglomerate with one another, and compact, cake or adhere to other objects that the granules move over or contact.

It is found that the Form II varieties, in marked contrast to the Form I varieties, hydrate extremely slowly (even though they have a higher immediate solubility than the Form I varieties!). This slow hydration behavior appears to be responsible for the aforementioned difficulties heretofore encountered when Form II triphosphates have been used in making detergent compositions, doubtless because a major portion of the water in the final dried product has been present as free water rather than as water of hydration.

2

It is an object of this invention to provide a method for the manufacture of non-sticky detergent compositions using Form II triphosphates and to reduce the dustiness of said detergent compositions.

More specifically the invention contemplates substantially complete hydration of Form II triphosphates in aqueous fluid detergent mixtures so as to prevent stickiness and reduce the dustiness of the dried detergent composition made therefrom.

I have discovered that suitable aging of aqueous fluid detergent mixtures containing Form II triphosphate prior to heat drying gives the unique and unexpected result of eliminating the sticky properties otherwise obtained in the heat dried detergent composition prepared therefrom. The time and temperature conditions of this aging are critical, as will subsequently be explained.

I have also discovered that this same aging greatly reduces the dustiness of the detergent product. The starting effect of aging is shown in a product, which was made from an aqueous detergent mixture containing Form II sodium triphosphate in particulate form that was aged for 8 hours before spray drying. It was a free-flowing, hard, non-sticky, tough, granular, non-dusty product that did not break down during the packaging operations. It had a dry feel even though it contained 10 per cent moisture. In direct contrast an identical batch of the same composition that was not aged before spray drying gave a sticky product that caked and lumped badly during the packaging operation even though it contained only 3 per cent moisture. In addition the granules were dusty and so fragile that they broke down to give more dust during the packaging operation.

I have further discovered that substantially complete hydration of the sodium triphosphate to the hexahydrate should be accomplished during the above mentioned aging period in the aqueous fluid detergent mixture.

In the accompanying illustrations

Figure 1 illustrates the conditions of time and temperature wherein approximately 10 per cent reversion of sodium triphosphate occurs during aging in the aqueous detergent compositions.

Figures 2 to 5 represent X-ray diffraction patterns characteristic of four different phosphates as follows:

Figure 2, anhydrous sodium triphosphate in the phase known as Form I,

Figure 3, anhydrous sodium triphosphate in the phase known as Form II,

Figure 4, sodium triphosphate hexahydrate, and

Figure 5, anhydrous sodium pyrophosphate.

In this specification and the appended claims I employ the term "detergent" to designate organic detergents, including:

(1) Ordinary soaps such as the alkali metal salts of the higher fatty acids that may be obtained from naturally occurring plant or animal esters or that may be produced synthetically (e. g. by oxidation of petroleum, or by hydrogenation of carbon monoxide by the Fischer-Tropsch process), resin acids and/or naphthenic acids.

(2) Synthetic organic detergents characterized by their high solubility in water, their resistance to precipitation by the constituents of hard water, and their surface active and effective detergent properties, which include:

(a) Anionic detergents (excluding true soaps), such as water-soluble salts of sulfuric and phosphoric acid reaction products of alkyl and substituted alkyl compounds containing from 8 to 18 carbon atoms in the alkyl group,

(b) Non-ionic detergents, such as the reaction products of higher alcohols and higher fatty acids with considerable amounts of alkylene oxides,

(c) Cationic detergents, such as certain quaternary ammonium groups and certain amine groups neutralized with acids each of which is preferably employed in its water-soluble salt form, bearing in mind, however, that some cationic detergents have but limited utility in strongly alkaline composition.

Numerous examples of such synthetic organic detergents are mentioned in Lind's U. S. Patent No. 2,396,278.

We include in the term detergent composition and/or detergent mixture, in addition to one or more of the above detergents, alkaline "builders" or detergent improving agents such as alkaline carbonates, silicates, phosphates and borates and/or such compounds as the perborates, persulfates and percarbonates; also organic builders, and perfumes, coloring matter, preservatives, and other substances commonly found in detergent compositions.

X-ray diffraction patterns show that the Forms I and II (see Figures 2 and 3) represent two different phases of sodium triphosphate having distinctly different crystalline patterns. Those spacings which are particularly useful for the identification of these forms in the presence of other phosphates are indicated on the patterns, (e. g. 2.68, 3.58, 3.71 and 8.1 angstrom units in Figure 3 ($\text{Na}_5\text{P}_3\text{O}_{10}$ -II)). Both forms take on water to form one and the same hydrate

however, the heat of solution of Form II is much lower than that of Form I, while the "immediate solubility" of Form II in water is greater than that of Form I. By immediate solubility is meant the amount of sodium triphosphate in solution at the end of 10 minutes solution time, (i. e. the solubility determined by mixing into 100 milliliters of water more than the amount of sodium triphosphate required to make a saturated solution and cooling to 25° C., and at the end of 10 minutes filtering, and evaporating at 105° C. a weighed portion of filtrate followed by drying at 500° C. The weight of dried material obtained per 100 gm. of solution is called the "immediate solubility"). Although various samples of Form II will show identical X-ray diffraction patterns they are frequently observed to differ widely in their "im-

mediate solubilities" and rates of hydration in water. The variation in hydration rate is particularly noticeable in detergent mixtures where the presence of other sodium salts, such as sodium alkyl sulfate, sodium sulfate, sodium carbonate, etc. tends greatly to repress the solubility of the triphosphate. Typical examples of these variations are illustrated below in Table I, wherein the samples of sodium triphosphate used had a particle size such that at least 100 per cent of the sample passed through a 35 mesh Tyler standard screen and 90 per cent passed through a 100 mesh screen.

Table I

Form	I	II	II
Variety	Rapid hydrator.	Moderate hydrator.	Slow hydrator.
Immediate solubility in gm. per 100 gm. water soln. 25° C.	15-----	20-----	30-----
Hours for hydration in aqueous detergent mixture.	1/6-----	1 1/6-----	5-----

This table shows two typical examples of the numerous variations encountered in the time needed for hydration of Form II sodium triphosphate. These hydration periods were determined by measuring the time required to reach substantially maximum mass viscosity of the detergent mixture containing the triphosphate as said phosphate absorbed the free water in the mixture and converted to the hexahydrate. These measurements were made with a commercially available instrument called the "Brabender Plastograph," which records continuously the torsion moment required to rotate a pair of agitators in the viscous mixture being examined.

I have found that the hydration of the triphosphate in the aqueous detergent mixtures can readily be accomplished by aging, within the temperature range of 120° to 200° F., in a manner adapted to prevent settling and separation of the undissolved salts. The aging may be effected in a vessel equipped with agitators or in numerous other devices, e. g. screw conveyors or long pipelines, wherein sufficient storage time is to be had to permit substantially complete hydration to the hexahydrate.

Sodium triphosphate is a metastable material in water solution. It hydrolyzes or reverts slowly to form normal and acid salts of other phosphoric acids, usually having a higher degree of molecular hydration. Thus excessively high temperatures or long aging periods are to be avoided since the larger amounts of reversion products obtained thereby reduce the efficiency and other desirable properties of the final detergent composition. In the practice of this invention it is my purpose to so regulate the operating conditions that reversion of the triphosphate will be less than 10 per cent. The curve in Figure 1 shows conditions of time and temperature for the aging operation at which approximately 10 per cent reversion is to be expected.

The invention will be better understood from the following examples in which all compositions are given in terms of percentage by weight or parts by weight.

Example I.—38 parts of a slowly hydrating Form II sodium triphosphate, having a particle size such that it would pass through a Tyler standard 35 mesh screen, were thoroughly mixed with 58 parts of an aqueous fluid containing 58%

water and 24% of sodium alkyl sulfate prepared by sulfating the fatty alcohols obtained by the reduction of coconut oil, and 4 parts of soda ash were then added. The somewhat thin slurry obtained therefrom was mixed thoroughly for 20 minutes and then aged for 6 hours at 165° F. during which time it was agitated by a slowly turning (15 R. P. M.) paddle type agitator that served to keep the slurry well mixed without incorporating large amounts of air. During the aging the slurry became a viscous but yet pumpable mixture which was then spray dried, in well known manner, yielding a highly satisfactory, rapidly dissolving, efficient detergent composition in solid granular form, that was free flowing, comparatively dustless, non-sticky and composed of tough granules that did not break down to any significant amount during subsequent packaging operations. Analysis showed it to contain 9% moisture.

The marked benefit obtained through the aging process is shown by comparing the product in Example I with a product obtained by spray drying a like, aqueous, detergent-triphosphate mixture that had not been aged. The latter was a sticky, fragile and dusty product, the particles of which caked and lumped, and broke down badly to form more dust during the packaging operation. This product contained only 3% moisture. Another portion of the same unaged slurry that was spray dried so as to leave 9% moisture in the product gave a damp material that balled badly when handled.

Example II.—32 parts of a moderately slowly hydrating Form II sodium triphosphate, having a particle size such that it would pass through a Tyler standard 35 mesh screen, were thoroughly mixed with 48 parts of an aqueous fluid containing 60% water and 23% sodium alkyl sulfate, and 14 parts of an aqueous fluid containing 65% water and 16.4% of alkyl benzene sulfonate, to which were added 5 parts of soda ash. The somewhat thin slurry obtained therefrom was aged by slowly agitating it for a total of 4 hours at a temperature of 170° F., during which period it gradually became a viscous but yet pumpable mixture. Said slurry was then spray dried in well known manner yielding a highly satisfactory, rapidly dissolving, efficient detergent composition, in solid granular form, that was free flowing, comparatively dustless, non-sticky and comprised of tough granules that did not break down to any significant amount during subsequent packaging operations. Analysis showed it to contain 10% moisture.

A product obtained by spray drying a slurry of like composition, but not aged, was a sticky, fragile and dusty product, the particles of which caked and lumped badly during the packaging operation. This product contained only 4% moisture.

Example III.—36 parts of a poorly hydrating Form II sodium triphosphate were thoroughly mixed with 59 parts of an aqueous fluid containing 60% water and 24% of sodium alkyl sulfate, and 5 parts of soda ash were then added. The somewhat thin slurry obtained therefrom was mixed thoroughly and then aged for 5 hours at 160° F. during which time it was agitated by a slowly turning (15 R. P. M.) paddle type agitator that served to keep the slurry well mixed without incorporating large amounts of air. During the aging the slurry gradually became a viscous but yet pumpable mixture which was then dried as a film or thin sheet over steam heated rolls, yielding a highly satisfactory, rapidly dissolving

efficient detergent composition, in diminutive flake form, that was free flowing, non-sticky and comprised of tough particles that did not break down to any significant amount during subsequent handling. Analysis showed the product contained 14% moisture.

Example IV.—29 parts of a slowly hydrating Form II sodium triphosphate, having a particle size such that it would pass through a Tyler standard 35 mesh screen, were thoroughly mixed with 68 parts of an aqueous fluid containing 65% water and 16.3% of alkyl benzene sulfonate, to which were added 5 parts of soda ash. The somewhat thin slurry obtained therefrom was mixed thoroughly for 20 minutes and then aged for 6 hours at 165° F. during which time it was agitated by a slowly turning (15 R. P. M.) paddle type agitator that served to keep the slurry well mixed. The mixture, which became more viscous during aging, was then spray dried in well known manner, yielding a highly satisfactory, rapidly dissolving, efficient detergent composition in solid granular form, that was free flowing, comparatively dustless, non-sticky and comprised of tough granules that did not break down to any significant amount during subsequent packaging operations. Analysis showed it to contain 7% moisture.

A product obtained by spray drying a slurry of like composition, but not aged, was a sticky, fragile and dusty product, the particles of which lumped very badly during the packaging operation. This product contained only 3% moisture.

It will be noted that in the detergent composition of each of the foregoing examples the Form II triphosphate is a major component and was, in fact, present in greater quantity than the organic detergent.

I have found that an aging period of six hours at 165° C. is, in most cases, sufficient for the treatment of commercial phase II sodium triphosphate used in the preparation of detergent compositions as hereinbefore described, and that with occasional lots, which represent moderately fast hydrating varieties, as little as one to two hours treatment will suffice; however, since an intent of the aging is to substantially complete the hydration of the triphosphate to the hexahydrate I generally employ such periods of time as are necessary to completely hydrate extremely slowly hydrating varieties of Form II that are infrequently encountered.

In the preceding specific examples detergents of each of the various types enumerated in defining the term may be substituted for the detergents specifically mentioned in the examples, with appropriate adjustment if desired of the proportions of the constituents to take care of any differences in active detergent ingredient content.

In the manufacture of detergents in particulate form it is desirable to regulate the size of the particles so that rapid solution of the final product in water will be obtained. In preparations such as the above examples where a major proportion of triphosphate is used, very little of the triphosphate is in solution at any one time during the processing operations, most of it being merely suspended as a slurry. Thus to insure the desired product solubility rate the triphosphate used should in general have a particle size no larger than that desired in the final product.

This invention in its broad aspects is not restricted to the manufacture of detergent mix-

tures containing in addition to the organic detergent only sodium tripophosphates but may also be applied in the manufacture of detergents comprising tripophosphates of potassium and other alkali metals. Nor is it limited to any particular type of manufactured detergent composition in which the alkali metal tripophosphate may be included, such as flakes, threads, powders or spray dried forms.

It is to be understood that the foregoing more particularly described processes are to be considered as illustrative of the preferred method only; such changes and modifications therein are contemplated as would normally occur to those skilled in the art to which the invention relates.

Having thus described my invention, what I claim and desire to secure by Letters Patent is:

1. In the process of manufacturing a heat dried detergent composition substantially free of dust and of stickiness and caking properties, the steps of incorporating Form II sodium tripophosphate in a fluid mixture containing essentially an organic detergent of the group consisting of alkali metal soaps and water soluble non-soap synthetic detergents and more than sufficient water to effect substantially complete hydration of the said tripophosphate to the hexahydrate, the amount of said tripophosphate incorporated being in excess of the amount of detergent; agitating and aging the mixture within the temperature range of 120° to 200° F. for at least one hour and until hydration to the hexahydrate is substantially complete as determinable by measuring the time required to reach a maximum in a mass viscosity test of a like mixture of said components, but no longer than that time represented by the point on the curve in Figure 1 which corresponds to 10 per cent reversion of the tripophosphate at the aging temperature employed; and heat drying the aged mixture to the solid form.

2. In the process of manufacturing a heat dried detergent composition substantially free of dust and of stickiness and caking properties, the steps of incorporating Form II sodium tripophosphate in a fluid detergent mixture containing as the active detergent ingredient a water-soluble salt of a member selected from the group consisting of sulfuric reaction products of alkyl and substituted alkyl compounds, and mixtures thereof containing from 8 to 18 carbon atoms in the alkyl group, and more than sufficient water to effect substantially complete hydration of the said tripophosphate to the hexahydrate, the amount of said tripophosphate incorporated being in excess of

the amount of detergent; agitating and aging the mixture within the temperature range of 120° to 200° F. for at least one hour and until hydration to the hexahydrate is substantially complete as determinable by measuring the time required to reach a maximum in a mass viscosity test of a like mixture of said components, but no longer than that time represented by the point on the curve in Figure 1 which corresponds to 10 per cent reversion of the tripophosphate at the aging temperature employed; and heat drying the aged mixture to the solid form.

3. In the process of manufacturing a heat dried detergent composition substantially free of dust and of stickiness and caking properties, the steps of incorporating Form II sodium tripophosphate in a fluid mixture containing essentially an organic detergent of the group consisting of alkali metal soaps and water soluble non-soap synthetic detergents and more than sufficient water to effect substantially complete hydration of the said tripophosphate, the amount of said tripophosphate incorporated being in excess of the amount of detergent; agitating and aging the mixture within the temperature range of 120°-200° F. for at least one hour and until hydration is substantially complete as determinable by measuring the time required to reach a maximum in a mass viscosity test of a like mixture of said components, but no longer than that time represented by the point on the curve in Figure 1 which corresponds to the aging temperature employed; and heat drying the aged mixture to the solid form.
